UNITED STATES PATENT OFFICE.

SAMUEL SNYDER, OF WHITE SULPHUR SPRINGS, MONTANA TERRITORY.

FIRE-ESCAPE.

SPECIFICATION forming part of Letters Patent No. 325,450, dated September 1, 1885.

Application filed April 14, 1885. (No model.)

To all whom it may concern:

Be it known that I, SAMUEL SNYDER, of White Sulphur Springs, in the county of Meagher and Territory of Montana, have invented a new and Improved Fire-Escape, of which the following is a full, clear, and exact description.

The invention consists in the combination, with a windlass-drum journaled in a frame, of a rope secured on the same, a brake-pulley formed on the drum, a brake-band passed around said pulley, and a rope secured to the brake-band.

Reference is to be had to the accompanying drawings, forming part of this specification, in which similar letters of reference indicate corresponding parts in both the figures.

Figure 1 is a plan view of my improved fire-escape. Fig. 2 is a cross-sectional elevation of the same on the line *x x*, Fig. 1.

A windlass-drum, A, is journaled in a frame, B, and has one end, C, of its shaft squared to receive a key for turning the drum. On one end of the said drum a brake-pulley, D, is formed, around which a steel brake-band, E, is passed, which has one end secured to the frame B, and has a rope, F, or wire secured to the other end.

A rope or band, G, is secured on the drum A and wound on the same, and to the free end of the said rope a belt, H, is secured. The frame B is secured on the floor of the room at the window in such a manner that the top of the frame B and the drum A are about level with or slightly above the window-sill J. The free end of the brake-band E projects toward or over the sill J, as shown.

If desired, the frame B can be secured to the sill or to the lintel.

In using the fire-escape the person secures the belt H around his body and grasps the brake-rope F and steps out of the window. Under the action of the person's weight the rope G unwinds, the revolution of the drum being controlled by the brake-band E. When the person arrives at the ground he unfastens the belt and the rope G is wound on the drum and the belt is raised and can be used by another person.

When the device is not in use, both ropes G and F are in the room. By means of the rope F the descent can be regulated by the descending person, or by a person in the street below, or the brake can be controlled by a person in the room.

Having thus described my invention, what I claim as new, and desire to secure by Letters Patent, is—

1. In a fire-escape, the combination, with a frame adapted to be secured inside of a room adjacent to a window, of a windlass-drum journaled in the upper part of the same, a rope secured on the drum, a brake-band passed around the drum, and a rope attached to the free end of the band, substantially as herein shown and described.

2. In a fire-escape, the combination, with the stationary frame B, of the windlass-drum journaled in the upper part of the said frame, the rope G, the belt H, the brake-pulley D, the brake-band E, and the rope F, substantially as herein shown and described.

SAMUEL SNYDER.
